[57] CLAIM

The ornamental design for a temperature sensor or similar article, substantially as shown and described.

DESCRIPTION

FIG. 1 is a perspective view of a temperature sensor or similar article, showing the new design;

FIG. 2 is a front edge view thereof with the tape and probe portions of the design removed for clarity;

FIG. 3 is a side elevational view thereof similar to FIG. 2;

FIG. 4 is a rear edge view thereof similar to FIG. 2;

FIG. 5 is a side elevational view similar to FIG. 2 showing the opposite side thereof;

FIG. 6 is a bottom elevational view thereof, with the tape and reader portions of the design removed for clarity and a portion of the probe of the design truncated also for clarity;

FIG. 7 is a side elevational view thereof, similar to FIG. 6;

FIG. 8 is a front view thereof, similar to FIG. 6 and;

FIG. 9 is a rear view thereof, similar to FIG. 8;

Fig. 5.

Fig. 2.

Fig. 3.

Fig. 4.
